Max Bloomberg, Long Island City, N. Y.

Application October 25, 1954, Serial No. 32,793

Term of patent 14 years

(Cl. D86—10)

To all whom it may concern:

Be it known that I, Max Bloomberg, have invented a new, original, and ornamental Design for a Combined Cosmetic Container and Mirror, of which the following is a specification, reference being had to the accompanying drawing, forming a part thereof.

container and mirror of Figure 1 showing the front cover open to expose the mirror.

I claim:

The ornamental design for a combined cosmetic container and mirror, as shown and described.
